(57) **CLAIM**

The ornamental design for a portion of an anti-asphyxia valve
for a respiratory mask as shown and described.

DESCRIPTION

FIG. 1 is a front perspective view of a portion of an anti-asphyxia valve for a respiratory mask according to our design;

FIG. 2 is a front view thereof;

FIG. 3 is a left side view thereof with the right side view being
a mirror image thereof; and,

FIG. 4 is a top view thereof with the bottom view being a
mirror image thereof.

The broken lines shown in the drawings represent structural
environment are for illustrative purposes only and form no
part of the claimed design. The dotted lines represent the
border between claimed and non-claimed subject matter and
form no part of the claimed design.
